UNITED STATES PATENT OFFICE.

GEORGE RAMSEY, OF BROOKLYN, NEW YORK, ASSIGNOR TO ANCHOR CAP AND CLOSURE CORPORATION, OF LONG ISLAND CITY, NEW YORK, A CORPORATION OF NEW YORK.

CAP AND DAUBER.

Application filed July 8, 1925. Serial No. 42,162.

The present invention relates to closure caps and packages and more particularly to caps and packages having daubers associated therewith.

5 An object of the present invention is the provision of a metallic closure cap to which a dauber may be readily and effectively secured without interfering with the subsequent sealing of the cap on a vessel.

10 Another object of the invention is to facilitate the attachment of a dauber to a metallic screw cap by providing in the cover portion of the closure a crescent shaped annular shoulder to which the coiled 15 upper end of the dauber shank may be attached.

A further object of the invention is the adaptation of a metallic screw cap for the attachment of a dauber thereto, wherein a 20 recess in the center portion of the closure is adapted to receive and securely retain the upper end of a dauber shank, and wherein an annular zone about the recess is adapted to seat a flat gasket, which may extend over 25 said recess and conceal the upper end of the dauber shank to form a perfect edge seal independently of the dauber attachment.

Other and further objects of the invention will be in part obvious and will in part be 30 pointed out hereinafter in the specification following by reference to the accompanying drawings forming a part of this application and wherein like parts are represented by like characters throughout the several figures 35 thereof.

Fig. 1 is a side elevational view of a vessel sealed in accordance with the present invention.

40 Fig. 2 is a detailed view of the dauber support ready to be applied to a closure.

Fig. 3 is a detailed cross sectional view showing a dauber applied to a closure; and

45 Fig. 4 is a detailed cross sectional view of a closure cap and dauber applied to a vessel.

In packaging liquids such as shoe polish, glue, and the like, it is desirable to afford the consumer some means of readily applying the contents of the packages to the articles or surfaces for which the liquids are adapted. The most satisfactory way of doing this is to seal the bottle by means of suitable gaskets and screw caps and to attach daubers or the like directly to the caps.

Such caps may be made readily and inexpensively by suitable machines from thin sheet metal and when applied to containers are positively held in position and not likely to become unsealed in transit or by subsequent handling. Furthermore, the caps 60 may be removed and replaced as often as desired without impairing in any way the effectiveness of the seal; and therefore the contents of the packages, not being subjected to contact with the atmosphere, may be kept indefinitely.

A convenient way of attaching a dauber to a screw cap is to coil the upper end of the dauber shank so that it may be contracted to engage the skirt of the cap and 70 retain the shank, extending downwardly therefrom, in proper position. Since the coil must be contracted for insertion into the cap, there is necessarily a space between the free ends of the coil and when a flat 75 gasket is placed over the coil in a closure cap for the formation of an edge seal on a suitable vessel, the existence of the coil between the gasket and the cover portion of the cap materially affects the sealing operation. For the best results the coil must be 80 of substantially the same size as the skirt of the cap and in that case it fits directly above the mouth of the vessel and since there is a gap in one portion of the coil, a perfect 85 seal is not feasible. The present invention eliminates these difficulties by providing a recess in the cover portion of the cap having a crescent shaped shoulder adapted to engage the outer edge of the coil when it is 90 sprung into the recess. A flat gasket may then extend over this coil and an edge seal 95 may be made with the gasket between the cover portion of the cap and the edge of the vessel.

Referring to the drawings, there is shown a container 1 threaded at its upper end to receive a metallic screw cap 2, having a cover portion 4 and a skirt 5. The skirt has suitable screw threads therein adapted 100 to engage the threads at the mouth of the vessel, and if desired, it may be finished with a wire edge at the lower part thereof. The cover portion of the cap has an annular flat zone 6 adjacent the skirt with the center portion of the cover raised out of the plane of the annular zone to form a recess 7. The side of the recess is preferably formed into

a crescent shaped shoulder 8, having a height substantially the same as the diameter of the wire to be attached thereto. A suitable wire is bent at one end into a resilient coil 10, as shown in Fig. 2, in a plane perpendicular to the downwardly extending shank 11, and has a radial portion 12 connecting one end of the coil to the shank. The coil 10 is preferably formed so that there is a slight space or gap 14 between its ends so that it may be contracted sufficiently to be inserted into the recess 7 of the cap to engage the shoulder 8 thereof and be retained in position. The downwardly extending shank 11 may be bent upwardly at 15 to accommodate a suitable dauber 16 for dispensing and applying polish or the like as desired.

A suitable gasket 17 having an aperture 18 at its center to fit about the shank 11 is adapted to fit into the upper part of the cap and to be seated on the annular zone 6. While the coil 10 is adapted to be held in place by the shoulder 8, the gasket 17 may be glued to the upper part of the cap or secured in any other suitable manner to the cover portion of the closure to supplement the action of the shoulder 8 and assist in holding the dauber securely in position. The outer edge of the gasket is adapted to lay between the zone 6 and the mouth of the vessel to form an effective edge seal when the closure is applied to the vessel.

It will be seen in the above construction that the attachment of the dauber to the cap does not affect the application of the gasket to the cover, nor does it affect the subsequent sealing operation. The outer edge of the gasket is engaged between the zone 6 and the mouth of the vessel to form a very effective seal. The recess 7 in the cover portion of the cap holds the dauber rigidly in position and permits the gasket 17 to fit smoothly thereover. Such a construction is both pleasing in appearance and effective in operation.

It must be understood that many variations can be made from the preferred embodiment described herein without departing from the spirit of the invention, and the above description is therefore to be taken as illustrative and not in a limiting sense.

Having thus described my invention, what I claim is:—

1. As an article of manufacture, a metallic closure having a cover portion with an annular zone about its outer edge adapted to seat a gasket, the center portion of the cover being raised out of the plane of said zone to form a recess in the upper part of the closure having a depth substantially equal to the diameter of the wire to be seated therein, a wire adapted to receive a dauber at its lower end and having its upper end coiled to seat resiliently in said recess where-

by said wire is attached to the closure, and a skirt depending from said cover portion having screw threads therein for engagement with a vessel.

2. The combination of a vessel having 70 suitable screw threads at the mouth thereof, a closure cap having a threaded skirt adapted to engage the mouth of said vessel, a cover portion having an annular zone adjacent said skirt, the center part of said cover 75 being raised out of the plane of said zone to form a cup shaped recess with the lower periphery reduced in size, a wire having its upper end coiled to be sprung into said recess and having its lower end adapted to accommodate a dauber, and a gasket adapted to be seated on said annular zone to form an edge seal on said vessel.

3. As an article of manufacture, a metallic closure having a skirt adapted to engage the mouth of a vessel, a cover portion having an annular zone adjacent said skirt adapted to seat a gasket, the center portion of said cover being raised out of the plane of said zone to form a cup shaped recess 90 having the lower periphery thereof reduced in size to receive and retain the coiled upper end of a suitable wire.

4. As an article of manufacture, a metallic closure cap having a skirt adapted to 95 engage the mouth of a vessel, a cover portion having an annular zone adjacent said skirt adapted to seat a gasket, the center portion of said cover being raised out of the plane of said zone to form a recess of 100 sufficient depth to receive a single coil of wire with the side wall thereof extending outwardly and upwardly to form an abutment on the bottom of the recess.

5. As an article of manufacture, a metallic closure cap having a skirt adapted to engage the mouth of a vessel, a cover portion having an annular zone adjacent said skirt adapted to seat a gasket, the center portion of said cover being raised out of the plane of said zone to form a recess of sufficient depth to receive a single coil of wire, with the side wall thereof extending outwardly and upwardly to form an abutment on the bottom of the recess, and a dauber 110 comprising a shank and a single coil of wire on the upper end thereof adapted to be sprung into said recess above said abutment.

6. An article of manufacture, a closure having a cover portion provided with an annular zone adjacent its outer edge adapted to seat a gasket, the central portion of said cover portion being raised from said zone to form a pocket with the side walls thereof being recessed to a larger diameter than the mouth of said pocket, a wire supporting member having its upper end provided with a resilient head adapted to seat into said pocket and be held therein by resilience of said head pressing against the

recessed portion of the side walls of said pocket above the mouth thereof, and a depending skirt adapted to engage the mouth of a suitable vessel.

5 7. An article of manufacture, a closure cap having a top portion provided with an annular zone adjacent its outer edge adapted to seat a gasket, the central part of said top portion being disposed out of the plane of
10 the said annular zone to form supporting

means, the side wall of said supporting means having a recess formed therein, a supporting wire being provided on one end with a resilient coil and being attached to said cap by the resilience of said coil bearing against the side wall of said supporting means, a gasket within said cap, and a skirt depending from said top portion to secure said cap to the mouth of a suitable vessel.

GEORGE RAMSEY.
